UNITED STATES PATENT OFFICE

EMIL M. JOHNSON, OF GORMAN, SOUTH DAKOTA

LOCK FOR TRACK DOORS

Application filed September 23, 1929. Serial No. 394,574.

This invention appertains to closure fasteners and more particularly to a novel latch for sliding doors.

One of the primary objects of my invention is to provide an improved latch for sliding doors which is so constructed that there will be no projecting parts in the doorway, thereby permitting the free passage of draft animals and the like through the door opening without danger of the harness catching in parts of the latch.

Another important object of my invention is to provide a latch for sliding doors which can be readily and quickly applied to the door and door frame and which is so constructed that when the parts are in their interconnected position movement of the door both laterally and longitudinally of the door frame is precluded.

20 A further salient object of my invention is to provide a latch for slide doors embodying a manipulating handle for the door operatively connected to the latch member, whereby when pull is exerted on the handle, the latch member will be moved out of engagement with the keeper carried by the door frame.

25 A further object of my invention is the provision of novel means for retaining the handle in its normal position, said means also constituting a thumb piece for permitting the operation of the latch from the inside of the door.

30 A still further object of my invention is to provide an improved latch for sliding doors of the above character, which will be durable and efficient in use, one that will be simple and easy to manufacture, and one which can be incorporated with a conventional slide track door and frame at a small cost.

35 With these and other objects in view, the invention consists in the novel construction, arrangement and formation of parts, as will be hereinafter more specifically described, 40 claimed, and illustrated in the accompanying drawings, in which drawings:

45 Figure 1 is a fragmentary side elevation of a door and door frame showing my improved latch incorporated therewith and in its operative position;

Figure 2 is a fragmentary edge elevation of the meeting edge of a sliding door showing my improved latch incorporated therewith and with the door frame;

Figure 3 is a vertical section taken on the line 3—3 of Figure 2 looking in the direction of the arrows;

Figure 4 is a horizontal section taken on the line 4—4 of Figure 1 looking in the direction of the arrows;

Figure 5 is a vertical section taken on the line 5—5 of Figure 4 looking in the direction of the arrows and illustrating the novel operating handle and the thumb piece normally retaining the handle in its operative position;

Figure 6 is a view similar to Figure 4 showing the position of the operating handle when the latch is being actuated;

Figure 7 is a fragmentary detail perspective view of the frame for the latch proper, and

Figure 8 is a detail perspective view of the keeper which is adapted to be secured to the door frame.

45 Referring to the drawings in detail, wherein similar reference characters designate corresponding parts throughout the several views, the letter A generally indicates my improved latch for a door B slidably mounted longitudinally of a door frame C.

The door B is of the type generally employed for barns and like structures and is slidably supported from a suitable trackway carried by the upper portion of the door frame, and the door is adapted to slide over the outer face of the door frame C to close the door opening, as clearly shown in Figure 4 of the drawings. In accordance with my invention, the forward edge of the door is provided with a horizontal slot 10 at the point where the body portion of the latch is to be associated therewith.

50 My improved latch A includes a frame 15 preferably formed from strap iron or the like and is bent from a single strip of metal and includes inner and outer side plates 16 and 17 and a connecting front plate 18 which overlies the front of the slot 10. If preferred, the opposite faces of the door B can be cut so that

the side plates 16 and 17 can be countersunk therein. A suitable bolt 19 extends through the door B and through the inner ends of the side plates 16 and 17 for holding the frame in position. The inner plate 16 is provided with a slot 20 which registers with the slot 10 in the door and alines with a keyhole shaped slot 21 formed in the front plate 18. The purpose of the slots 20 and 21 will herein-after more fully appear, and it is to be noted that the plate 17, at its point of connection with the front plate 18, is provided with a vertical slot 22. A barrel 23 is carried by the inner face of the outer plate 17 and extends into the slot 10 of the door B and surrounds an opening 24 formed in the outer plate 17. The inner plate 16, in direct transverse alinement with the barrel 23, is provided with an enlarged opening 25, for a purpose which will be later described. If preferred, a smaller bolt 26 can be passed through the door and the inner and outer plates 16 and 17 adjacent to the front edge and on each side of the slot 10 in the door for holding the plates in position against movement.

Secured to the outer face of the door frame C is the keeper element 26 which is also preferably made from sheet metal suitably bent and pressed into the desired form. The keeper 26 includes a tapered barrel portion 27 having a keeper notch 28 therein at a point intermediate its ends; and the barrel 27 is connected with the attaching flanges 29 by side connecting walls 30. The attaching flanges 29 are provided with openings 31 whereby the keeper can be readily secured to the outer face of the door frame, and it is to be noted that when the door is moved to its closed position, the tapered barrel portion 27 will ride into the keyhole shaped opening 21 and into the slot 10 formed in the door. Owing to the construction of the barrel and the keyhole slot 21, lateral shifting movement of the door relative to the frame is precluded.

A latch bar 32 extends through the vertical slot 22 and is adapted to ride on the tapered outer face of the barrel 27 and into the notch 28 for retaining the parts in their latched position. The latch bar 32 is formed on and bent at right angles to the arm 33 of the U-shaped manipulating handle 34, the inner end of which can be provided with an eye 35 so as to permit the connection therewith with the bolt 19, whereby the handle will be held in proper position.

A slide rod 36 extends through the barrel 23 and opening 24 and is provided with an outer hooked end 37 which extends through an opening 38 formed in the handle 34. The outer end of the rod 36 is provided with a thumb-piece 39 which may be in the nature of a nut and which is normally disposed within or adjacent to the opening 25, the wall of which may be tapered toward said thumb piece. An expansion spring 40 is coiled

about the rod 36 and is placed within the barrel 23 and bears respectively against the thumb piece 39 and the inner face of the plate 17. This normally holds the handle in its inner position and the latch bar 32 in engagement with the keeper.

It is preferred to make the handle of resilient material whereby when pull is exerted on the handle the same will flex so as to move the latch bar 32 from out of the keeper recess 28. It is obvious, however, that the handle can be connected by means of a hinge joint with the eye 35, if preferred.

In operation of the improved latch, the door is closed in the ordinary manner and it is obvious that the inclined end of the latch bar 32 riding on the inclined face of the barrel 27 of the keeper will spring the handle and latch bar outwardly and when the latch bar comes into alinement with the keeper recess 28, the same will spring into the keeper recess or notch and thereby prevent sliding movement of the door relative to the door frame.

When it is desired to open the door, the handle 34 can be grasped and pulled outwardly which will flex the same and allow the keeper bar 32 to be moved out of the keeper notch, after which the door can be slid on its track to open the same. It is also obvious that it is merely necessary to press upon the thumb piece 39 when it is desired to operate the latch from the inside of the door.

From the foregoing description it can be seen that I have provided a novel latch particularly adapted for sliding doors in which no projecting parts are made in the door frame.

Changes in details may be made without departing from the spirit or the scope of this invention, but:

What I claim as new is:

1. A latching mechanism of the class described, comprising a frame adapted to be secured to a door and having a notch formed at one end thereof adapted to receive a keeper, and a second notch formed in said frame opposite said first mentioned notch, a resilient handle secured to said frame and provided with an inwardly extending latch bar passing through said second mentioned notch adapted to engage a keeper, a transversely extending barrel formed upon the inner face of said frame, a spring-pressed rod slidably mounted within said barrel and guided in its movements thereby, said rod engaging said handle and normally holding the same in a locked position and permitting yieldable outward movement of said handle for the purpose of unlocking the same.

2. A latching mechanism of the class described, comprising a comparatively flat casing comprising a pair of substantially parallel members having one end connected by means of a front plate, said parallel members

provided with a longitudinally extending notch communicating with a cut-out portion formed in the front plate to constitute a keeper-receiving notch, said casing provided
5 with a slot at the junction of the front plate with one of the side members and said slot being arranged opposite said keeper receiving slot, a handle secured to said casing and provided with an outwardly extending hand-
10 gripping loop, the forward end of the handle normally lying snugly against said casing and provided with an inwardly extending end passing through said last mentioned slot, a spring-pressed rod carried by said casing,
15 guiding means for said rod, said rod provided with an angularly bent end engaging said handle for normally holding the handle in a locked position.

20 In testimony whereof I affix my signature.
EMIL M. JOHNSON.
